STITCHING MACHINE

William R. Spiller and Robert J. Niederhauser,
Dayton, Ohio, assignors, by mesne assignments,
to Acme Steel Company, Chicago, Ill., a corporation of Illinois

Application January 14, 1943, Serial No. 472,316

19 Claims. (Cl. 1-2)

1

This invention relates to wire stitching machines.

It is the principal object of the invention to provide a wire stitching machine adapted to form flat, tight-fitting stitches in hard material such as sheets of metal or the like and having long life and freedom from excessive wear in the stitching of such material.

It is a further object to provide such a machine in which the parts subject to severe wear in use are constructed for maximum life and arranged to be quickly and easily replaced when necessary without the use of special tools or equipment.

It is a further object to provide for easily and readily adjusting the position of the clincher mechanism in order to locate it in precise position with respect to the location of the stitch and to securely retain the parts in such adjusted position.

It is a further object to provide a construction in which adjustment may be readily made for stitching materials of different thickness without disturbing the driving connections as established for the actuation of the clincher mechanism.

Other objects and advantages will be apparent from the following description, the accompanying drawing, and the appended claims.

In the drawing:

Fig. 1 is a view in side elevation of a stitching machine constructed in accordance with the present invention with certain parts being broken away to more clearly show the construction thereof;

Fig. 2 is a horizontal broken sectional view looking downwardly on the adjustable ways which provide for vertical adjustment of the clincher arm;

Fig. 3 is a broken view of the outer end of the clincher arm showing the clincher mechanism;

Fig. 4 is a view on a somewhat larger scale of the die holder and the dies, being shown partially in section and partially in plan;

Figs. 5, 6 and 7 are three elevational views looking toward the front face of the dies and clincher plunger assembly and showing three successive stages in the formation and clinching of the stitches, certain parts being broken away;

Fig. 8 is a side elevational view of the clincher plunger itself;

Fig. 9 is a view partly in plan and partly in section showing a modified construction of clincher assembly;

Fig. 10 is a broken front elevational view of this modified construction;

2

Fig. 11 is an end elevational view of the die of Figs. 9 and 10; and

Fig. 12 is an end elevational view of the clincher plunger.

5 Referring to the drawing which discloses a preferred embodiment of the invention, the machine is shown as having a main frame including a base portion 10, an upwardly projecting pedestal 11, and an overhanging head 12. The 10 drive motor 14 is mounted in the rear portion of the head and has a suitable driving connection to the main shaft 15. Shaft 15 extends through the head to the front part thereof where the mechanism for forming and driving the stitches 15 is located, the position thereof being indicated by reference numeral 16. A coil of wire 17 is mounted in a convenient location on the head and the wire feeds into the stitch forming mechanism in the usual way where it is formed into an inverted U-shaped stitch, the two legs of the stitch being driven downwardly into and through the work material received beneath the head.

An arm 20 is provided on which the work is received, such arm also carrying the clincher 25 mechanism which provides for clinching the two legs of the stitch after they have been forced through the work material and flattening the legs upon the face of the material. Both the arm and the frame are of sturdy construction 30 being preferably formed as relatively heavy castings, to provide a rigid structure having a minimum of deflection under the loads encountered in use. Arm 29 is adjustably carried on the pedestal, and is so mounted as to have vertical 35 adjustment thereon to accommodate work material of different thickness, and also is arranged to have lateral adjustment to properly center the clincher mechanism with respect to the location at which the stitch is formed.

40 To provide for obtaining such adjustment the face of pedestal 11 is formed with the spaced ways 22 and with vertical bearing surfaces 23 against which corresponding surfaces of the arm are adapted to bear. The arm is formed with 45 rearwardly extending projections 24 within which there are mounted studs 25 having engagement with wedge shaped gibs 26 adapted to bear against the ways 22, respectively, end plate 27 preventing lateral displacement of the gibs. 50 By suitably adjusting the studs 25, it will be evident that the entire arm can be shifted laterally from one side to the other while still maintaining its firm support upon the ways, and when so adjusted and with the wedges again tightened 55 it will be securely retained in such adjusted posi-

tion. Preferably three such sets of bolts 25 are located in vertically spaced relation on arm 20 to provide maximum security and accuracy of positioning. It will be clear also that with the bolts 25 spaced vertically as shown, it is possible to loosen the uppermost while tightening the lowermost, and vice versa, and in this way rock the arm about its longitudinal axis as may be necessary to maintain it level and parallel with the forming mechanism.

In order to secure vertical adjustment in the location of the arm while at all times maintaining the arm in desired level horizontal relation, the arm is provided with apertured portions 30 adjacent its inner end which are adapted to receive locking bolts 31 threadedly received in the face of the pedestal 11, and extending through enlarged slots 32 in the rear face of the arm at the upper part thereof. The enlarged slots permit adjustment both vertically and laterally and the bolts at the top of the arm take the load in tension and support the arm firmly. A pair of downwardly projecting lugs 34 is provided on the lower face of the arm 20 and a connecting pin 35 having a threaded part 36 is secured thereto. A pair of nuts 37 are threadedly received on pin 36 and are located on opposite sides of an abutment 38 secured to the face of the pedestal. Thus it will be apparent that having first loosened bolts 31, the entire arm may be raised or lowered upon the pedestal to adjust the position of the arm to a different level by suitably adjusting either the upper or the lower of the nuts 37. The nuts 37 and bolts 31 are then again tightened to securely lock and retain the arm in adjusted position. Since it is desirable to have as little movement of the arm as possible in the course of the stitching operation, the gibs 26 are preferably set up to such an extent that they tightly hold the arm and preferably with sufficient frictional force to prevent downward movement thereof under the action of gravity. The arm can however be readily actuated either up or down by the means described above, and thus adjustment is simplified while at the same time maintaining firm and secure support for the arm throughout its operation. Suitable indicating and index means may be provided as desired to facilitate the setting of the arm.

The clincher mechanism is located at the outer end of the arm and comprises a die holder or block 40 suitably positioned in a recessed part of the arm and attached thereto by means of bolt 41. The position of the clincher mechanism lengthwise of the arm may be accurately determined by means of a threaded bolt 42 which bears against the upright face of the recessed portion as clearly shown in Fig. 3. In order to adjust the position of the clincher mechanism in this direction therefore it is only necessary to loosen bolt 41 and make suitable adjustment in the position of bolt 42, following which bolt 41 is again tightened to retain the die block in properly adjusted position. The die block is received within and guided at each side by the recess in arm 20, and rests at its lower side directly on arm 20 so that it is firmly and securely held in proper fixed positioning when so adjusted.

The die block is formed with a central upwardly extending portion 44 at its forward end and at opposite sides thereof is formed with outwardly extending arm portions 45 which on their forward faces are suitably recessed as clearly

shown at 46 in Fig. 4. Within these recesses there are received, respectively, the two cooperating die members 48, the dies being themselves bored and counterbored to receive attaching bolts 49 which thread into the arms 45 and thus detachably secure the dies in position upon the die block. In such position the dies are securely held against any movement by reason of the formation of the recesses in the die block at the sides and the arm 20 providing support from below.

As shown in Fig. 4, the opposing faces of each of the dies 48 are formed with a groove or slot 50 which extends throughout the full height of the die. This groove or slot has a width closely conforming with the diameter of the wire, being preferably only slightly larger than the wire diameter to provide for receiving the ends of the legs of the stitch with only a limited clearance therefor. It will be understood that with the leg received within the groove in the die, the stitch is guided and supported around substantially the entire outer half of its periphery. The portion of the slot below the tapered portion is rectangular in section as shown in Fig. 4.

As shown in Figs. 5, 6 and 7 the slot 50 itself is of less extent than the outside length of the stitch, but the upper or leading end of the guide slot is beveled or tapered and is semi-circular in section as indicated at 52 and this taper is such that the opening at the top of the slot is of sufficient extent to initially receive the advancing ends of the legs of the stitch, and to guide the legs inwardly producing an inward inclination thereof. As a result of the inward inclination in the legs of the stitch so produced, the clincher in the course of its operation completes the bending and flattening of the legs against the face of the material.

The actual extent of this taper has been found to be important since with too small a taper, the legs will not be bent in sufficiently to be flattened by the plane top surface of the plunger. Thus where the inclination was such as to provide a taper less than about half the wire diameter, it was found that in many cases the operation of the plunger would cause the ends of the wire to be doubled back upon itself, rather than bending the legs into a flat clinch relation. On the other hand where the taper was greater than the wire diameter, an objectionable condition of curl was obtained in the legs themselves, and it was difficult to flatten the legs into a tight clinch against the surface of the material and there was some tendency to spread the hole inwardly as the wire was clinched. Best results have been consistently obtained where the extent of the taper was less than the leg diameter, but somewhat greater than half the leg diameter. It will be understood, however, that with different types of material to be stitched, and with wire of different modulus of elasticity and tensile strength, some change in these relationships may be effected.

The dies are subject to substantial wear in the vicinity of the tapered groove, and for the purpose of securing the maximum of wear from each pair of dies, they are made symmetrically at opposite ends so that by inverting and switching the dies to opposite sides of the die block, they may be reassembled with a new tapered slot and thus the effective life of the dies is substantially doubled.

A clincher plunger 55 is arranged for travel in a reciprocating path of movement in the two guide slots 50 formed by the opposing die mem-

bers, the plunger being of substantially the same thickness as the diameter of the wire and having a width corresponding to the extent of the slot 50 and hence such as to fit closely within the guide slot while being freely movable therein. To provide additional strength and stiffness, the plunger is formed with a front portion 56 of less width than the rear portion, such front portion moving freely in spaced relation between the two side faces of the dies themselves. This front portion 56 preferably projects upwardly above the clincher surface 57 a distance of about half the wire thickness so as not to strike and deface the surface of the work, forming a forward retaining edge 58 as shown in Fig. 8 which serves the purpose of guiding the ends of the legs into the desired flat relation and preventing forward movement thereof during the course of the clinching operation. Preferably the clinching surface 57 is plane lengthwise of the stitch and is grooved transversely as shown in Fig. 8 with a curvature corresponding closely with that of the periphery of the wire to receive the wire therein and to provide for additional guiding of the wire during the clinching operation. Both ends of the plunger are similarly shaped, and because of the severe usage to which it is subjected it is provided with a pair of equally spaced apertures 59 so that it can be assembled in either of two relatively inverted positions affording additional life and wear. Backward movement of the wire is prevented by the front face of the die block itself and the wire is thus completely guided in all directions.

For the purpose of actuating the clincher plunger, the drive shaft 15 is provided with a cam 60 which actuates a connecting rod 61, such rod in turn operating a ball crank lever 62 pivotally supported at 63 on frame 11. The opposite end of the bell crank engages a push rod 64 which is mounted for movement in a substantially longitudinal direction in the frame, and projects parallel with the arm 20 and into a position adjacent the inner end and below the working surface thereof. Arm 20 carries a push rod 65 supported in extensions formed in the lower side of the arm and in a protected position beneath the working surface thereof, push rod 65 being parallel to and having abutting engagement with the end of rod 64. In order to provide for maintaining the operative relationship established between the two rods 64 and 65 throughout the extent of the vertical and lateral adjustment of the arm 20, one or the other of these rods is provided with an extended bearing surface so that proper engaging relation is maintained notwithstanding relative travel of the arm and its rod 65. In the form shown, rod 64 is sufficiently large in diameter so that it will have proper driving relation with rod 64 in all relative positions thereof.

Suitable means are likewise provided for adjustment in the extent of movement of the clincher plunger and in the upper elevation which it reaches, to determine the force with which the plunger bears against the clinch, and the extent to which it is flattened against the work. Such adjustment can be incorporated at any suitable point in the clincher actuating mechanism and the adjustment may be made accessible either from the rear of the pedestal or from a protected position beneath the arm. In the arrangement shown, the rod 65 terminates in a butt end, and an intermediate connecting rod 68 is mounted coaxially therewith and supported in the web portions 69 of the arm 20. A bolt 70

having a head 71 is threaded into a recess in the end of connecting rod 68 and a lock nut 72 provides for moving the head of the bolt closer to or farther from the end of push rod 65. It will be obvious that in this way the effective length of the connecting rod 68 is altered and such change causes a greater or less travel of the clincher plunger.

Having secured the proper adjustment of the clincher plunger operation, the arm 20 may be then reset for work of different thickness, and notwithstanding the raising or lowering of the arm, it is not necessary to readjust the operation of the clincher plunger, as it retains its setting and will provide for making the same type of clinch on the new work as on the work of different thickness, this being a distinct advantage where work of different thickness is being handled.

20 In the outer end of the arm 20 there is mounted a pin 75 which serves as the pivot for a bell crank lever 76. The lever is notched out as shown at 77 and receives the forward driving end of the connecting rod 68, such rod when moved toward the left in an operating stroke of movement causing a rocking of the bell crank in a clockwise direction as shown in Fig. 3. The bell crank also is formed with a downwardly extending yoke portion 78 which is adapted to be received in the rear of a pin 79 also carried by connecting rod 68 to provide for reverse rocking of the crank in response to the opposite travel of the connecting rod.

Projecting from the other side of the crank 76
35 is a round pin 80 which is received within the lower aperture 59 of the clincher plunger when the plunger is assembled in the groove in the dies. It will thus be clear that in response to travel of the connecting rod to the left in Fig. 3,
40 motion will be imparted through the bell crank and the pin 80 to the clincher plunger to lift the same upwardly in a stroke of clinching operation while the plunger is guided by the guide slots 50. Return movement of the connecting rod is obtained under the action of a compression spring 82 one end of which bears against the web element 69, and the other end against a collar 83 secured to the connecting rod 68, and provided with a suitable handle 84 readily accessible beneath arm 20.

Because of the severe wear upon the clincher plunger, it is usually found necessary to remove and replace this part at somewhat frequent intervals. In accordance with the present invention this is accomplished with great ease and without the necessity for disassembling the dies. It is only necessary to grasp the handle 84 and to pull the connecting rod 68 forwardly against the action of spring 82, to a point such that the bell 55 crank is rocked beyond its normal range of operating movement and into the dotted line position shown in Fig. 3 where as will be clear the pin 80 is withdrawn from aperture 59, providing for direct downward withdrawal of the plunger 60. Similar action provides for the reassembly of either the same plunger in inverted position, or another plunger, the plunger being inserted in the guides 50 with the bell crank manually rocked into the dotted line position and the handle then 65 released with the pin 80 returning into engaging relation in the lower of the apertures 59. While it is possible also to remove the bolts 49 and with them the two die members 48, such operation is 70 preferably followed only when it is desired to re-
75 move and invert or replace the die members

themselves, such operation ordinarily not being required as frequently as replacement of the plunger.

It is usually found that with stiff and hard metal sheets such as sheets of Duralumin used in the fabrication of airplane parts for instance, the presence of the dies surrounding and giving support to the outer half of the periphery of each leg of the stitch results in a clean hole being punched with little tendency to enlarge or tear out the hole. As the legs of the stitch are forced into the stiff material, the ends thereof tend to act as punches forcing a chip or slug of the metal in advance of the wire and discharging it downwardly through the opening in the dies. Such chips usually cling to the material on the inside of the legs of the stitch and if desired means may be provided for facilitating the removal of such chips so that they will not be caught beneath the legs of the stitch. For this purpose the die block is cored as shown at 90 and connection is made to a suitable source of air pressure. The passage 99 communicates with a pair of upwardly extending passages 91 formed in the part 44 of the block, the passages 91 opening on the front face of the block as shown at 92, immediately adjacent the inside of the legs of the stitch, at the points where the chips usually tend to cling. Suitable valve means may be provided for controlling the air supply to have it in operation as the stitch is being formed, such mechanism being conveniently controlled from the trip mechanism which places the machine in operation.

With somewhat softer sheet material there is some tendency for the downwardly moving stitch to draw the metal, and this condition is also noted more particularly where three or more sheets are being stitched. In the latter case, and particularly where the intermediate sheet or sheets is of softer material, it has been found that the stitching action results in drawing the metal of the intermediate sheet or sheets downwardly with the stitch, providing a firm and secure interlocking of that sheet with the next lower sheet, thereby forming an extremely tight and secure connection.

In operation, the drive motor actuates the shaft 15 in response to being tripped, preferably by a manual trip control in the usual manner, causing the stitch forming mechanism to form a stitch and causing that stitch to be driven downwardly through the work material placed at the outer end of the arm. It will be clear that material of widely varying sizes and shapes may be handled, and may be received over the arm in any convenient position, a back gage 86 being provided upon the upper face of the arm to assist in the setting of the work at a definite location.

The clincher operation is timed in predetermined relation to the stitch forming and driving operation as shown in the sequential series of views represented in Figs. 5, 6 and 7. The initial formation of the stitch is shown in Fig. 5 with the legs being partially driven through the sheet material and guided inwardly by the beveled portions 52, the slugs being indicated at 94. In Fig. 6 the stitch has been completely formed and driven downwardly, the downwardly extending legs being bent inwardly as shown prior to contact with the upper surface of the clincher plunger and the slugs have been separated and dropped out of the way. In Fig. 7 the clincher plunger has completed its stroke and has flattened the legs down upon the surface of the material, thus com-

pleting the operation, the parts then being returned to their initial position in preparation for a subsequent cycle of operation.

Adjustment of the arm either laterally or vertically does not disturb the drive mechanism for operating the clincher and the accurate horizontal relation of the arm is maintained throughout such adjustment. Likewise adjustment of the position of the die block assembly on the arm does not affect the drive mechanism. The adjustment in the effective length of the push rods is made very easily and provides for adjusting for the height of the arm and causing the plunger to move to clinching position with the desired degree of force, without requiring any other change in the driving connections.

As a specific example the machine was constructed to form a stitch having a space between the inner sides of the legs of $\frac{1}{8}$ inch using wire of .050 inch diameter and having a tensile strength of from 270,000 to 320,000 pounds per square inch. The outermost extent of the groove at the top of the tapered portion was the same as that of the outside spacing of the legs of the stitch. Where the taper was about .020 to .025 inch on each side, or less, it was found that there was a tendency for the collapsing or folding back of the leg upon itself and a failure to turn the leg inward sufficiently to be properly engaged by the plunger. On the other hand with a taper in excess of the diameter of the wire, i. e. above about .050 inch, there was a tendency to produce an objectionable curl in the leg which was not entirely removed by the plunger and thus the clinch was not sufficiently flat. Most satisfactory results were secured where the taper varied from about .030 to .040 inch at each side. With such a taper very satisfactory stitches were secured upon two hard metal sheets such as stainless steel or Duralumin, each of a thickness of approximately .040 inch.

A somewhat modified construction is shown in Figs. 9 to 12. In this construction the two dies 100 are bolted in place on die block 101 and are provided with cooperating grooves 102 the inner ends of which are semi-circular in cross section and are so mounted upon the die holder that the grooves extend for the full length of the stitch and hence no tapered lead-in is provided at the ends. The dies are relieved as shown at 103 with a front portion 104 adapted to engage with the corresponding portion on the opposite die, to thereby close across the front of the dies for added protection. Also if desired the rear face of the die may be removed as indicated at 105, this space with the relief provided at 103 affording a passage through which any chips or slugs can be discharged.

The plunger is shown at 106 and is of substantially the same cross length as the combined extent of slots 102 so that it overlies the entire lower face of the stitch and is rounded at its outer sides to fit closely within and to be guided by the slots 102. In order to provide for the inward turning of the ends of the stitch legs, the upper face of the plunger is provided with upwardly raised ear portions 107 at opposite sides thereof, these ears making initial engaging contact with the legs of the stitch and turning the same inwardly toward each other. As the stroke of the plunger is completed, it bears against the entire lower face of the stitch and with particular pressure against the ends thereof, to assure the clinching in a firm and tight manner. The radius of curvature of the ears is approximately that of the bend of the wire at the corners, so

that a flattening pressure is applied uniformly across the entire extent of the stitch. The upper surface of the plunger may be plane transversely, or may be grooved as shown at 108 in Fig. 12, to afford additional guiding contact for the wire as the legs are being flattened. Both the dies and the plunger are symmetrically formed so that they can be reversed for additional use, as described above.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. In a wire stitching machine of the character described having a base and an upwardly extending pedestal portion, forming a main frame for the machine and an overhanging head including a stitch forming mechanism, vertically extending ways on said frame, a clincher arm, means for mounting said arm for vertical adjustment on said ways including gibs bearing respectively against said ways, and means for individually adjusting said gibs to provide for lateral shifting of said arm upon said ways to locate and secure the clincher mechanism in accurate relation with respect to the stitch forming mechanism.

2. In a wire stitching machine of the character described having a base and an upwardly extending pedestal portion, forming a main frame for the machine and an overhanging head including a stitch forming mechanism, vertically extending ways on said frame, a clincher arm, clincher mechanism carried by said arm, means for mounting said arm for vertical adjustment on said ways, operating mechanism carried by said arm for effecting actuation of said clincher mechanism, means operable separately and independently of the vertical adjustment of said arm for adjusting the extent of travel of said clincher mechanism, drive means mounted on said frame, said drive means and said operating means having cooperating parts maintained in predetermined driving relation throughout the vertical travel of said arm to maintain a predetermined setting of said adjustable means throughout different positions of vertical adjustment of said arm.

3. In a wire stitching machine of the character described having a base and an upwardly extending pedestal portion, forming a main frame for the machine and an overhanging head including a stitch forming mechanism, vertically extending ways on said frame, a clincher arm, clincher mechanism carried by said arm, means for adjusting the extent of travel of said clincher mechanism, means for mounting said arm for vertical adjustment on said ways, a push rod carried by said arm for actuating said clincher mechanism, a drive rod mounted in said frame, one of said rods having a relatively extended engaging surface providing for maintaining the operating engagement thereof and a predetermined setting of said adjusting mechanism substantially unaffected by the vertical travel of said arm.

4. In a wire stitching machine of the character described having a base and an upwardly extending pedestal portion, forming a main frame for the machine and an overhanging head including a stitch forming mechanism, vertically extending ways on said frame, a clincher arm,

clincher mechanism operably carried by said arm including a clincher plunger, means for mounting said arm for vertical adjustment on said ways, means for adjusting said clincher mechanism to cause a greater or less travel of said clincher plunger to apply a predetermined clinching pressure to the ends of said stitch, means carried by said frame for driving said clincher mechanism, and means for maintaining the driving relationship between said drive means and said clincher mechanism over the range of vertical adjustment of said arm while maintaining a predetermined adjustment of the travel of said clincher plunger.

5. Clincher mechanism for a wire stitching machine comprising die members having a guide slot therein, a plunger movable in said slot to effect the clinching of the stitch, an actuating mechanism connected with said plunger for moving said plunger through a normal cycle of movement within said slot, and manual means for effecting the disconnection of said actuating mechanism and said plunger to free said plunger and provide for continued movement thereof in said slot to a position where it is entirely withdrawn therefrom.

6. Clincher mechanism for a wire stitching machine comprising die members having a guide slot therein, a plunger movable in said slot to effect the clinching of the stitch, an actuating mechanism for moving said plunger through a normal cycle of movement within said slot including a pin engaging said plunger to effect reciprocation thereof in a normal cycle of movement, and means for manually moving said pin to a position beyond its normal range of reciprocating travel to effect disengagement thereof from said plunger providing for free removal and replacement of said plunger in said guide slot.

7. Clincher mechanism for a wire stitching machine comprising die members having a guide slot therein, a clincher plunger mounted for reciprocating travel in said slot to effect the clinching of the stitch, a bell crank having a pin projecting therefrom and engaging an aperture in said plunger, means for normally actuating said bell crank to effect said reciprocating travel of said plunger, and means for modifying the action of said actuating means to provide for movement of said bell crank to a position beyond its normal range of travel such that said pin is withdrawn from the aperture in the plunger providing for direct withdrawal and replacement of the plunger in said guide slot.

8. Clincher mechanism for a wire stitching machine comprising die members having a guide slot therein, a clincher plunger mounted for reciprocating travel in said slot to effect the clinching of the stitch, a bell crank having a pin projecting therefrom and engaging an aperture in said plunger to effect said reciprocating travel of the plunger, a push rod for normally actuating said bell crank, and manual means accessible beneath said arm for moving said push rod and said bell crank to a position beyond the normal range of reciprocating travel thereof providing for withdrawal of said pin from the aperture in the plunger releasing the plunger for direct removal and replacement in said guide slot.

9. Clincher mechanism for a wire stitching machine comprising a die holder, die members secured to said die holder in predetermined cooperating relation and having guide slots for receiving the ends of the stitches as they are formed and enclosing substantially half the periphery of

each end of the stitch, and a clincher plunger movable in and guided by said guide slots and movable into engaging and flattening relation with the ends of said stitches, said plunger being symmetrically formed at its opposite ends and adapted to be inserted in said guide slots in either of two relatively inverted positions to effect clinching of the stitch and to provide longer life.

10. Clincher mechanism for a wire stitching machine comprising a die block, die members for receiving the legs of the stitch as it is forced through the material and provided with guide slots, said die members having guide surfaces spaced apart a distance corresponding substantially to the outside spacing of the legs of the stitch and being formed with portions having an inward taper at each side less than the thickness of said legs and greater than half the thickness thereof, said taper extending over a substantial vertical distance such that the legs of said stitch are turned inwardly but remain substantially uncurled, and a clincher plunger movable in said guide slots to engage the inwardly turned legs of the stitch to flatten the same against the work material.

11. Clincher mechanism for a wire stitching machine comprising a die block, means forming die members for receiving the legs of the stitch as they are forced through the material, said die members having tapered guide surfaces the outer edges of which are spaced apart a distance corresponding substantially to the outside spacing of the legs of the stitch and being formed with parallel portions forming guide slots below said tapered part which are spaced apart a distance greater than the space between the legs of the stitch but less than the outside length of the stitch, and a clincher plunger movable in said guide slots to engage the inwardly turned legs of the stitch to flatten the same against the work material.

12. In clincher mechanism for a wire stitching machine having a die block, a pair of die members for receiving the ends of the wire as the stitch is forced through the material, each of said die members having a guide slot therein for receiving the advancing end of the leg of the stitch while providing support for substantially the outer half of the periphery thereof, each of said die members being symmetrically formed at opposite ends with a similar guide slot to provide for assembly of said die members in inverted position to afford additional wear thereon.

13. In clincher mechanism for a wire stitching machine having a die block, a pair of die members adapted to be secured to said die block in either of two relatively inverted positions, said die members each having a guide slot formed therein and symmetrically positioned to provide for assembly of said die members in two positions relatively inverted with respect to each other in each of which said guide slots cooperate to form a die for receiving the opposite ends of the legs of the stitch as said legs are forced through the material to be stitched and a clincher plunger mounted for reciprocating travel in said guide slots to clinch and flatten the legs of said stitch upon the face of the work material.

14. In clincher mechanism for a wire stitching machine having a die block, a pair of die members adapted to be secured to said die block in either of two relatively inverted positions, said die members each having a guide slot formed therein and symmetrically positioned to provide for assembly of said die members in two posi-

tions relatively inverted with respect to each other in each of which said guide slots cooperate to form a die for receiving the opposite ends of the legs of the stitch as said legs are forced through the material to be stitched, and a clincher plunger mounted for reciprocating travel in said guide slots to clinch and flatten the legs of said stitch upon the face of the material, said plunger being symmetrically formed to be received in two relatively inverted positions within said guide slots to provide for additional wear thereon.

15. Clincher mechanism for a wire stitching machine having a die block comprising die members each having a guide slot formed therein extending uniformly to the upper edge thereof, means for assembling said die members upon said die block in cooperating relation with said respective guide slots correlated to provide for receiving the respective ends of the stitch in substantial parallel relation as the same is formed, a clincher plunger movable into clinching position within said guide slots to flatten the legs of said stitch upon the face of the material, said guide slots and said plunger having a length substantially the same as the outside length of the stitch itself, said plunger having upwardly extending ears adjacent its opposite ends to receive the ends of the legs and to initiate a bend therein in preparation for the flattening thereof against the material and to apply flattening pressure across the entire extent of the stitch.

16. Clincher mechanism for a wire stitching machine having a die block comprising die members each having a guide slot formed therein, means for assembling said die members upon said die block in cooperating relation with said respective guide slots correlated to provide for receiving the respective ends of the stitch as the same is formed, a clincher plunger movable into clinching position within said guide slots to flatten the legs of said stitch upon the face of the material, said clincher plunger having a work engaging end adapted to engage the legs of said stitch and to press the same flat against the material, said plunger also having a part located forwardly of the plane of said guide slots and projecting above said work engaging end to prevent forward displacing movement of the ends of the legs and to restrain said legs within the plane of the stitch.

17. Clincher mechanism for a wire stitching machine comprising a die block, means carried by said die block forming die members for receiving the ends of the wire stitch as the stitch is forced through the material, said die block having air supply means in line with a part of each leg of the stitch which projects through the work material, and means for supplying air pressure to said air supply means to discharge air jets therefrom directly against the chips formed by each leg of the stitch to effect removal thereof.

18. In a stapling machine, a base carrying a stationary die, a staple clinching die movable relative to said stationary die, a rocker pivotally mounted upon said base and having a knob portion extending into a recessed portion of said clinching die for cranking the latter to move in directions transversely of the direction of extension of said knob portion, spring means tending to bias said rocker away from staple clinching procuring position, and means adapted to be manually operated to rotate said rocker against the forces of said spring means for displacing said rocker knob portion laterally out of connection with said die recessed portion.

19. In a stapling machine, a base, a stationary die mounted on said base, a staple clinching die movable relative to said stationary die, a rocker pivotally mounted upon said base and having a knub portion extending into operating connection with a recessed portion of said clinching die, spring means tending to bias said rocker away from staple clinching position, and means carried by said rocker adapted to be manually operated upon to actuate said rocker against the forces of said spring means for rotating said rocker knub portion out of connected relation with respect to said clinching die member, whereby said movable die member may be freed of connection to said rocker to permit removal of said die from said machine.

Certificate of Correction

Patent No. 2,424,717.

July 29, 1947.

WILLIAM R. SPILLER ET AL.

It is hereby certified that errors appear in the printed specification of the above numbered patent requiring correction as follows: Column 5, line 38, for "ball" read *bell*; column 10, line 74, for "stiches" read *stitches*; column 14, after line 16, add the following reference—

1,761,536 *Price* ..... *June 3, 1930*
and that the said Letters Patent should be read with these corrections therein that the same may conform to the record of the case in the Patent Office.

Signed and sealed this 7th day of October, A. D. 1947.
